(57) **CLAIM**

The ornamental design for a shoebox lamp, as shown and described.

DESCRIPTION

FIG. 1 is a top, front and left side perspective view of a shoebox light showing my new design;

FIG. 2 is a top, rear and right side perspective view thereof;

FIG. 3 is a bottom, rear and left side perspective view thereof;

FIG. 4 is a top plan view thereof;

FIG. 5 is a bottom plan view thereof;

FIG. 6 is a left side elevational view thereof;

FIG. 7 is a right side elevational view thereof;

FIG. 8 is a rear elevational view thereof; and,

FIG. 9 is a front elevational view thereof.

The broken lines in the drawings illustrate portions of the shoebox lamp which form no part of the claimed design.
